UNITED STATES PATENT OFFICE

119,978

DESIGN FOR A BROOCH OR SIMILAR ARTICLE OF JEWELRY

Gladys Shaw Erskine, New York, N. Y.

Application June 1, 1939, Serial No. 85,284

Term of patent 3½ years

To all whom it may concern:

Be it known that I, Gladys Shaw Erskine, a citizen of the United States, residing at New York, in the county of New York and State of New York, have invented a new, original, and ornamental Design for a Brooch or Similar Article of Jewelry, of which the following is a specification, reference being had to the accompanying drawing, forming part thereof.

Fig. 1 is a front view of a brooch, showing my new design;

Fig. 2 is a bottom plan view thereof.

I claim:

The ornamental design for a brooch or similar article of jewelry, as shown.

GLADYS SHAW ERSKINE.
